UNITED STATES PATENT OFFICE.

JOSEPH WILLIS BISHOP, OF SALT LAKE CITY, UTAH, ASSIGNOR TO UTAH POWER & LIGHT COMPANY, OF SALT LAKE CITY, UTAH, A CORPORATION OF MAINE.

CABLE-TERMINAL.

1,258,304.

Specification of Letters Patent.

Patented Mar. 5, 1918.

Application filed February 24, 1917. Serial No. 150,711.

To all whom it may concern:

Be it known that I, JOSEPH W. BISHOP, a citizen of the United States, residing at Salt Lake City, Salt Lake county, and State of Utah, have invented and discovered certain new and useful Improvements in Cable-Terminals, of which the following is a specification.

My said invention relates to terminal pieces for cables and consists in the combinations and arrangements of elements hereinafter described and particularly set forth in the accompanying claims.

The invention has for its purpose to provide a cable terminal which will be securely held to the cable strands without the aid of set-screws or other like devices that readily work loose in service; and wherein the tensile strength of the cable is in no manner lessened by employing the terminal piece.

The invention has for its further purpose to provide a terminal piece for cables used as conductors for electrical purposes, in which perfect contact is made between the cable and the terminal piece, and between the terminal piece and the point of attachment.

Another purpose of the invention is to construct a cable terminal piece employing but few parts, that may be readily fitted to, or removed from, the cable, and in which the union between the cable strands and the terminal piece will be augmented in direct proportion to the strain to which the cable is subjected.

The invention is disclosed by way of illustration in the accompanying drawings, wherein—

Figure 1 is an elevational view showing the application of the invention,

Fig. 2 a transverse sectional view thereof, taken on the line 2—2 of Fig. 1,

Fig. 3 a longitudinal sectional view, taken on the line 3—3 of Fig. 1,

Fig. 4 a detail view of the bushing,

Fig. 5 a longitudinal sectional view of the device *per se*, and showing a modification,

Fig. 6 a similar view showing a further modification,

Fig. 7 a transverse sectional view illustrating a different design in the construction of the terminal piece, and

Fig. 8 a like view showing another de-

Referring to the construction in further detail and wherein like reference characters indicate corresponding parts, A designates the cable, of any general construction, and composed of twisted strands after the well-known manner; and said cable, whether made of wire or fiber strands, is adapted to be provided with the terminal piece forming the subject matter of the present invention.

The terminal piece *per se* consists of a bushing or sleeve 8 adapted to be fitted on the end portion of the cable, after the manner shown in Fig. 3; and said bushing is rendered readily expandable by having a plurality of longitudinal slots 9 formed therein for substantially the length of said bushing. The cable end having the bushing thereon is adapted to be fitted into and secured in the tubular member 10 of the terminal piece, 75 and which is formed with an integral web portion 11, giving the necessary contact surface at the point of attachment.

The means for securing the cable in the terminal piece 10 consists of a tubular core 80 or plug 12, of substantially the length of the terminal piece and having a tapered or wedge edge 13 for penetrating between the strands of the cable from the inner or open end 14 of the tube member 10; and said core 85 is constructed with a solid or closed end 15 for the application of a suitable tool or member used in driving the wedge into the end of the cable, as will be understood. When thus inserted into the cable end, said 90 tubular core receives or embraces the central strands of the cable and radially expands all strands exterior thereof, as shown in Figs. 2 and 3.

The outer end 16 of the terminal member 10 is formed with a constriction, and that portion of the cable end, together with the bushing 8, within the member 10, is adapted to be radially expanded or spread through the wedging action of said core 100 12 (see Fig. 3); and it will therefore be seen that said constriction serves as a stop or abutment, to prevent the withdrawal of the cable from the terminal member 10. It will be further noted that any strain on the 105 cable A would operate only to cause a greater wedging or clamping action between the cable and the terminal piece and this in a measure directly proportional to the degree of force thus exerted.

The construction of terminal piece disclosed in Fig. 5 is substantially the same as that above described and operates after the same manner. The core 17 is, however, in this instance, provided with an open inner end 18, as in certain uses of the device, this construction of core piece may be preferred. This form of the device also omits the use of the bushing or sleeve 8, and therefore by the strands of the cable are spread directly against the interior surface of the tubular part 10 of the terminal piece.

The terminal piece, as disclosed in Fig. 6 employs a wedge or core 19, having a solid and threaded portion 20 that screws into the threaded aperture 21 in the body 22 of the terminal member; and a nut-head 23 is formed on the core to receive a wrench or other tool for adjusting the core to the desired position. In all other respects the details of the terminal piece shown in Fig. 6 are the same, and operate in the same manner, as that of the terminal piece shown in Fig. 5.

25 The invention further contemplates constructing the device in different designs in cross-section for certain special uses, and this adaptation is shown, for instance, in Fig. 7 where the tubular member 24 of the piece is shaped substantially after the manner of a triangle, and, in like manner, the core member 25 is similarly designed in cross-section.

In the form shown in Fig. 8, the tubular member 26 is octagonal in cross-section, and the core member 27 is substantially square. These illustrations (*i. e.* Figs. 7 and 8) are sufficient to show that the device is susceptible of being constructed in various cross-sectional designs, as conditions might determine; and other forms in cross-section may also be made.

It is obvious that those skilled in the art may vary the details of construction and arrangement of parts without departing from the spirit of my invention, and I therefore do not wish to be limited to such features except as may be required by the claims.

50 Having thus fully described my said invention, what I claim as new and desire to secure by Letters Patent, is:—

1. A cable terminal piece comprising a terminal member of uniform cross section having a constricted opening at one end and adapted to receive the end of the cable, and a member for radially expanding the cable strands uniformly against said terminal

member to the inner side of said constricted opening, substantially as set forth. 60

2. A cable terminal piece comprising a terminal member of uniform cross section having a constricted opening at one end and adapted to receive the end of the cable, and a core of uniform cross section for penetrating the cable end to radially expand the cable strands uniformly against said terminal member to the inner side of said constricted opening, substantially as set forth. 65

3. A cable terminal piece comprising an open-ended tubular terminal member of uniform cross section having one end thereof constricted, and adapted to receive the end portion of the cable; and a tubular wedging core adapted to penetrate between the strands of the cable from the inner end of the tubular member and radially expand the cable strands uniformly against said terminal member for the entire portion of 70 said tubular member to one side of said constriction, substantially as set forth. 75

4. A cable terminal piece comprising an open-ended tubular terminal member of uniform cross section having one end thereof constricted, and adapted to receive the end of the cable; and a tubular core co-extensive in length with said terminal member and formed with a tapered end adapted to penetrate between the strands of the cable from the inner end of the tubular member and radially expand the cable strands uniformly against said terminal member for the entire portion of 80 said tubular member to one side of said constriction, substantially as set forth. 85

5. A cable terminal piece comprising an expansible bushing adapted to be fitted on the end portion of the cable, a tubular terminal member having a constricted end and 90 adapted to receive said bushing and the cable; and a tubular wedging core adapted to penetrate between the strands of the cable and radially expand the cable strands and said bushing against said terminal member 95 for substantially the entire length of said tubular member to one side of said constriction, substantially as set forth. 100

In witness whereof, I have hereunto set my hand and seal at Salt Lake City, Utah, 110 this 17th day of February, A. D. nineteen hundred and seventeen.

JOSEPH WILLIS BISHOP. [L. S.]

Witnesses:

OSCAR ILLI,
L. J. WALTERS.
